United States Patent

Des. 240,345
Patented June 29, 1976

240,345

SEAT OR SIMILAR ARTICLE

Matthew F. Callahan III, Corte Madera, Calif., assignor to Monastery Furniture Manufactory, Rohnert Park, Calif.

Filed Apr. 29, 1975, Ser. No. 572,779

Term of patent 14 years

Int. Cl. D6—01

U.S. Cl. D6—71

FIG. 1.

FIG. 2.

FIG. 3.

FIG. 4.

FIG. 5.

FIG. 6.

FIG. 7.

FIG.
8.

FIG. 1 is a perspective view of a seat or similar article showing a first embodiment of my new design;

FIG. 2 is a side elevational view thereof;

FIG. 3 is a front perspective view of the seat of FIG. 1 shown in the form of a settee;

FIG. 4 is a top plan view of the embodiment of FIGS. 1 and 2;

FIG. 5 is a front elevational view thereof;

FIG. 6 is a cross sectional view of the seat or similar article embodying my new design;

FIG. 7 is a rear elevational view thereof; and

FIG. 8 is a bottom plan view thereof.

I claim:

The ornamental design for a seat or similar article, substantially as shown and described.
